DESIGN FOR A CLOCK

Robert J. Moffatt, Birmingham, Mich.

Application September 20, 1945, Serial No. 122,216

Term of patent 14 years

(Cl. D42—7)

To all whom it may concern:

Be it known that I, Robert J. Moffatt, a citizen of the United States of America, residing at Birmingham, in the county of Oakland and State of Michigan, have invented a new, original, and ornamental Design for a Clock, of which the following is a specification, reference being had to the accompanying drawing, forming a part thereof.

Fig. 1 is a front elevational view of a clock showing my new design;

Fig. 2 is a rear elevational view;

Fig. 3 is a side elevational view; and,

Fig. 4 is a top plan view thereof.

I claim:

The ornamental design for a clock, substantially as shown.

ROBERT J. MOFFATT.
